DESIGN FOR A BOX

Frank McIntosh, New York, N. Y., assignor to Lenthalic Incorporated, New York, N. Y., a corporation of New York

Application July 1, 1938, Serial No. 78,203

Term of patent 7 years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof.

In the drawing:

Fig. 1 is a top plan of a box embodying my new design;

Fig. 2 is a front elevation thereof; and
Fig. 3 is an end elevation thereof.
The pairs of closely spaced parallel lines represent grooves.

I claim:

The ornamental design for a box, substantially as shown and described.

FRANK McINTOSH.
